INVENTOR
J. E. SULLIVAN

By Frank Brown Linley May
ATTORNEY

UNITED STATES PATENT OFFICE.

JOSEPH E. SULLIVAN, OF MELROSE, MASSACHUSETTS.

CUP-HOLDER.

1,207,092.

Specification of Letters Patent.

Patented Dec. 5, 1916.

Application filed February 17, 1916. Serial No. 78,899.

To all whom it may concern:

Be it known that I, JOSEPH E. SULLIVAN, a citizen of the United States, residing at Melrose, in the county of Middlesex and 5 State of Massachusetts, have invented new and useful Improvements in Cup-Holders, of which the following is a specification.

This invention has for its object to provide, as an attachment for dentists' chairs, 10 a holder for individual drinking cups, adapted to be detachably secured to a fixture on the chair, such as the usual vertical rod or spindle employed for supporting a cuspidor at one side of the chair, the attachment being adapted to hold a nest of inverted tapering cups, usually of paper, in such position that a patient occupying the chair may readily remove the upper cup of the nest for use, the other cups remaining in 20 the attachment, and the nest being projected upward after the removal of each cup, to locate the next cup in position for subsequent removal and use.

The invention is embodied in the 25 improvements hereinafter described and claimed.

Of the accompanying drawings forming a part of this specification: Figure 1 represents a side elevation of a cup holder embodying my invention; Fig. 2 represents an 30 end view of the same; Fig. 3 represents a partial section on line 3—3 of Fig. 2; Fig. 4 represents a section on line 4—4 of Fig. 1; Fig. 5 represents a top plan view of the 35 washer holder and washer hereinafter referred to; Fig. 6 represents a partial bottom plan view of said holder and washer; Fig. 7 represents a section on line 7—7 of Fig. 5; Fig. 8 represents a side elevation of 40 the portion hereinafter called the frame, showing a modification.

The same reference characters indicate the same or similar parts in all the views.

My improved cup holder or cup-holding 45 attachment comprises an elongated frame which includes a step 12 at one end of the frame, a ring 13 at the opposite end, and an elongated back bar to opposite ends of which said step and ring are secured, the step and 50 ring being rigidly held suitably spaced apart by the back bar.

I prefer to make the back bar adjustable in length to permit a variation of the spacing of the step and ring. To this end the 55 back bar may be composed of two members 14 and 14^a, one adapted to slide lengthwise

relatively to the other. As here shown the member 14 is a rod fitted to slide in an apertured ear 15 on the member 14^a, a set screw 16 being provided to secure the members at 60 any desired adjustment. The back bar is provided with means whereby it may be secured to a dentist's chair or to a fixture thereon, such as the vertical rod 18 located at one side of the chair and usually employed to support a cuspidor. I have embodied said means in a lateral ear 19 attached to the member 14^a and apertured to receive the rod 18, said ear having a set, screw 20, whereby it may be adjustably and 70 detachably secured to the rod.

The frame, when engaged with the chair rod, is adapted to move with the chair, and is held in a vertical position at one side of the chair with its upper end in convenient 75 relation to a patient occupying the chair.

The step 12 may be detachably and adjustably secured to the back bar member 14 by means of an apertured ear 22 on the step having a set screw 23.

24 represents an elongated tube, preferably of glass, bearing at its lower end on the seat 12 (the latter being recessed to receive the tube, as shown by Fig. 1), and embraced at its upper end by the ring 13. 85 Within the tube 24 and supported by the step 12 is spring 25, preferably helical, adapted to exert upward pressure on a nest of tapering inverted cups 26. The ring 13 is formed to permit the upward withdrawal 90 of the upper cup through it, and is provided with means yieldingly engaging the enlarged mouth portion of the upper cup, and limiting the upward movement of the nest by the spring 25, said means permitting the withdrawal by the patient of the upper cup, which is held by the spring partially projected above the ring. I have embodied 95 said means in an inwardly projecting annular flange 27 on the upper edge of the ring, the opening bounded by said flange being of greater diameter than the mouth of a cup 26, and a flexible elastic washer 28 clamped between the flange 27 and the upper end of the tube 24, the internal diameter of said washer being less than the greatest diameter of a cup 26. The washer yieldingly engages the mouth portion of the upper cup, and permits the upward withdrawal of the said cup by the patient, the washer automatically 105 engaging the mouth portion of the next cup.

I do not claim the above described cup-

engaging and releasing means independently, similar means having been heretofore employed to coöperate with a nest of cups, arranged in upright (not inverted) position and fed downward by gravity. I have however improved the means heretofore employed by providing the washer holder, shown by Figs. 5, 6 and 7. Said holder is a sheet metal ring 30 of greater internal diameter than the washer 28, so that when the ring is superimposed on the washer, the inner edge of the washer projects inwardly from the inner edge of the ring.

The outer edge portion of the ring or holder 30 is cut to form integral ears 31, which are forced through slits in the washer and bent against its under side, as shown by Figs. 6 and 7, said ears forming hooks firmly securing the washer to the holder. The bent portions of the hooks may be straightened to permit the removal of a spent washer, and the substitution of another therefor, so that it is not necessary to discard the holder. The washer and its holder are clamped between the flange 27 and the upper end of the tube 24.

The ring 13 is detachably secured to the back bar, so that it may be removed to permit the insertion of a nest of cups in the upper end of the tube. As here shown, the ring is provided with an ear 33 fitting a socket 34 in an ear 35 formed on the upper end of the back bar member 14^a. A thumb screw 36 engaging tapped orifices in the ears 33 and 35 detachably connects said ears. The lower ear 15 on the member 14^a is preferably provided with a band 37 embracing the tube 24.

Fig. 8 shows the step 12 and ring 13 connected by a non-adjustable back bar 14^b having a rod-engaging ear 19.

The ear 35 and the holding-down ring 13 constitute a two-part head forming one end of an elongated frame, and the step 12 fixedly spaced from said head constitutes the opposite end of said frame. The support-engaging means embodied in the perforated ear 19 and set screw 20 enable the ear 35 to be fixedly supported and the frame to be mounted in a vertical position beside a dentist's chair with the upper cup of the nest in position for removal by the occupant of the chair, the holder as a whole being so located relatively to the chair that it does not obstruct the movements of the dentist while operating on a patient in the chair.

The means for detachably securing the ring 13 to the ear 35 enable the holder to be conveniently charged with cups, by simply removing the ring, inserting a nest of cups in the upper end of the tubular casing 24, the cups at the same time compressing the spring 25, and then replacing the ring to cause it to hold down the cups and spring, the casing and spring remaining in posi-

tion, and being confined against lateral displacement, when the ring is removed, by means provided for that purpose and embodied, as here shown, in the band 37.

The construction of the holder may be variously modified within the scope of the appended claims, without departing from the spirit of the invention.

Having thus described my invention, I claim:

1. A dispensing holder for inverted cups, comprising an ear provided with support-engaging means whereby said ear may be fixedly supported, a separately formed ring separably associated with said ear and provided with yielding cup-engaging means, said ear and ring forming one end of an elongated frame, a step fixedly spaced from said ear and forming the opposite end of the frame, a spring seated on said step and adapted to press a nest of cups toward said ring, a tubular casing extending from the step to the ring, and laterally confining the spring, and means for detachably securing the ring to the fixed ear to permit the charging of the holder with cups, the said holder being formed to stand vertically beside a dentist's chair, and adapted to yieldingly hold the upper cup of a nest in position for removal by the occupant of the chair.

2. A dispensing holder for inverted cups, comprising a vertically elongated frame including a head forming the upper end of the frame, and provided with support-engaging means, and with means for embracing and yieldingly opposing upward movement of a nest of inverted cups, said means permitting the upper cup to project above the head, and a step fixedly spaced from said head, and forming the lower end of the frame, a spring seated on said step and adapted to exert upward pressure on the nest of cups, and a tubular casing extending between said step and head to laterally confine the spring and cups, a portion of the head being independently removable to permit the charging of the holder, and means being provided to prevent lateral displacement of the casing and spring when said portion is removed.

3. A dispensing holder for inverted cups, comprising a two-part head including an ear provided with supporting-engaging means, and a downwardly facing holding-down ring formed separately from said ear, and adapted to surround a nest of inverted cups, said ear and ring being provided with complementary coupling members permitting the quick attachment and detachment of the ring, a yielding washer held down by the ring for engaging the upper cup and yieldingly opposing upward movement of the nest of cups, a step located below and fixedly spaced from said head, a spring seated on said step and adapted to exert upward pressure on the cups, and a tubular casing ex-

tending from the step to the head to prevent lateral displacement of the spring, the removal of the ring and washer permitting the insertion of a charge of cups and the compression of the spring thereby, means being provided for laterally supporting the casing when the ring and washer are removed.

4. A cup holder for dental chairs, comprising an elongated back bar having means whereby it may be secured in a substantially vertical position to a fixture on a chair, a step attached to the lower end of said bar, a ring attached to the upper end of the bar, an elongated tube seated at its lower end on said step and embraced at its upper end by said ring, said bar being composed of two members, one adapted to slide relatively to the other to vary the length of the bar and the distance between the said step and ring, and provided with means for securing the members at various adjustments, and a spring supported by said step within the

tube and adapted to exert upward pressure on a nest of inverted tapering cups inserted in the tube, the ring being provided with means yieldingly confining the nest against the upward pressure of the spring, and permitting the upward withdrawal of the upper cup from the nest.

5. In a cup holder of the character described, a yielding cup-engaging device comprising an annular sheet metal washer holder provided with integral flexible hooks, and an annular elastic washer wider than said holder and slotted to receive said hooks, the inner edge of the washer being within the inner edge of the holder and adapted to engage the mouth portion of a tapered cup, and the washer being detachably connected with the holder by said flexible hooks.

In testimony whereof I have affixed my signature.

JOSEPH E. SULLIVAN.
